Horace T. Robbins Inventor

United States Patent Office.

HORACE T. ROBBINS, OF BOSTON, MASSACHUSETTS.

Letters Patent No. 91,565, dated June 22, 1869.

IMPROVEMENT IN UMBRELLA-RUNNERS

The Schedule referred to in these Letters Patent and making part of the same.

To all whom it may concern:

Be it known that I, HORACE T. ROBBINS, of Boston, county of Suffolk, and State of Massachusetts, have invented a new and useful Improvement in Runners for Umbrellas and Parasols; and I do hereby declare that the following is a full, clear, and exact description of the construction and operation of the same, reference being had to the annexed drawings, making a part of this specification, in which—

Figure 1 is a side view of a runner having my improvement applied to it.

Figure 2 is a longitudinal section of the same.

Figures 3 and 4 are views of the inner sliding tube detached from the runner.

Figure 5 is a view of a runner, with the inner sliding tube partially withdrawn.

Figure 6 is a longitudinal section of a runner and umbrella-handle, showing the position of the runner when the umbrella is closed.

Similar letters refer to like parts in the different drawings.

a is the runner.

b is a chamber on the side of the runner.

c is a sliding tube inside the runner.

d is a stop-device on the tube *c*.

e is a slot in the tube *c*.

f is the umbrella-handle.

g is the fastening-spring of the umbrella.

h is a key-hole.

The nature of my invention consists in providing runners for umbrellas and parasols with a locking-device without the inconvenience of a key.

I construct my runner with a chamber, *b*, on the side of it.

When the umbrella is closed, the fastening-spring

of the umbrella-handle passes into this chamber, and the umbrella is locked.

Inside the runner, I arrange the tube *c*, having a slot coincident with that communicating with the chamber in the runner.

When I wish to open the umbrella, I partially withdraw the tube *c*, as seen in fig. 5, which operation depresses the fastening-spring *g*, thereby releasing the runner or unlocking the umbrella.

The projecting lips *d* serve as a stop-device to prevent the tube from being withdrawn too far.

By making the sides of the slot *e* in the tube *c* in the form of a cam, the umbrella may be unlocked by revolving the tube, instead of withdrawing it.

To render the umbrella still more secure from being dishonestly appropriated, I make a key-hole, *h*, in the chamber *b*, which is of no use, except to mislead those unacquainted with the operation of the inner sliding tube.

I claim—

1. An umbrella-runner, provided with an inner sliding or revolving unlocking-tube, substantially as described.

2. The combination of the runner *a* and sliding tube *c*, substantially as described and for the purpose specified.

3. The chamber *b*, in combination with the runner *a* and sliding tube *c*, substantially as described, and for the purpose specified.

February, A. D. 1869.

HORACE T. ROBBINS.
